Primary Examiner — Melanie Pellegrini

(74) Attorney, Agent, or Firm — Michael N. Cohen;
 Cohen IP Law Group PC(57) **CLAIM**

I claim the ornamental design for the ring, as shown and described.

DESCRIPTION

FIG. 1 is a top perspective view of a ring;

FIG. 2 is a front view of FIG. 1; and

FIG. 3 is a side view of FIG. 1.

The broken lines shown in the drawings illustrate portions of the ring that form no part of the claimed design.

1 Claim, 3 Drawing Sheets---
